UNITED STATES PATENT OFFICE.

HERBERT E. WENRICH, OF BERWICK, PENNSYLVANIA.

GAME.

1,414,106.

Specification of Letters Patent. Patented Apr. 25, 1922.

Application filed March 23, 1921. Serial No. 454,632.

To all whom it may concern:

Be it known that I, HERBERT E. WENRICH, a citizen of the United States, residing at Berwick, in the county of Columbia and 5 State of Pennsylvania, have invented certain new and useful Improvements in Games, of which the following is a specification.

This invention relates to games, and the primary object of the invention is to provide 10 an improved game which will be of interest to both young and old, and which will require considerable skill and strategy to be played successfully.

Another object of the invention is to provide 15 an improved game in which the game board is divided into camps or nations, representing the main countries of the Allies in the World War, and a central fortress or country representing the main country of 20 the Entente, the camps being connected together, and with the main country of the Entente side by a common battle ground, which is divided into spaces on which the men of the allied countries are adapted to 25 be moved, the object of the game being to see which country of the allied side can get all of their men into the central or enemy country first.

A further object of the invention is to 30 provide a game which will be a reminder of the World War of the above character, in which the battle ground is divided off in a novel manner, so as to render the playing of the game more interesting and intricate for 35 the players, certain of the spaces of the battle ground being marked to indicate hospitals to which the men are adapted to be sent or returned when they land on other spaces marked "Wounded," "Gassed," or 40 the like, other spaces of the battle ground being marked "Advance" "Retreat" and the like, and when the men of the various nations on the allied side reach the said spaces they are either advanced a certain 45 number of spaces or placed back a certain number of spaces according to the indicia marked on the mentioned spaces.

A still further object of the invention is to provide an improved game which will 50 present a novel and pleasing appearance, and which can be placed upon the market at a reasonable cost.

With these and other objects in view, the invention consists in the novel construction, 55 arrangement and formation of parts as will be hereinafter more specifically described,

claimed and illustrated in the accompanying drawings, forming a part of this specification, in which drawings:

Figure 1 is a plan view of the game board 60 showing in shade lines, the color scheme which is a feature of the game.

Figure 2 is a perspective view of a pair of dice, and

Figure 3 is a perspective view of one of 65 the men or counters used in the game.

Referring to the drawings in detail, wherein similar reference characters designate corresponding parts throughout the several views, the numeral 5 indicates a 70 game board, which is preferably made of pasteboard or the like of any desired size or configuration. The upper surface of the board at the corners thereof is marked to provide four camps or nations, 6, 7, 8, and 75 9, which as shown represent the four principal countries of the Allies, namely, the United States of America, England, France and Italy, and each of these camps or nations have arranged therein the flags of 80 these nations suitably colored. Each of the camps may be surrounded by a suitable wall or fortress 10 having a single gate or outlet 11. The central portion of the board may be provided with a relatively large cross 85 shaped fort 12 which may be surrounded by a relatively wide line 13, which may represent a wall or the like. The camps or spaces 6, 7, 8, and 9 are spaced from the relatively large port 12 and this space defines a runway or battle ground indicated by the numeral 14. This runway or battle ground 90 14 is divided into a plurality of spaces indicated by the numeral 15 and certain of these spaces have certain indicia written or 95 stamped thereon, the purpose of which will be hereinafter more fully described. At the central portion of the port 12 is a substantially rectangular campus 16, which forms the nation, fort or camp ground for the 100 main country on the Entente side, namely Germany, and in this campus or fortress 16 is placed the German flag 17. Radiating outwardly from the corners of the campus 16 and extending to the points of connection 105 of the arms of the fort are roadways 18, 19, 20 and 21, which are also divided into equal spaces 15'. Each of these roadways 18, 19, 20 and 21 constitute an entrance roadway into Germany for each of the countries 6, 110 7, 8 and 9. Directly in alignment with the gateway 11 of the countries 6, 7, 8, and 9

are spaces 22, 23, 24, and 25 which are colored the national color of the countries engaged, namely United States of America, blue; England, red; France, white; and 5 Italy, green, and these spaces 22, 23, 24 and 25 constitute the starting point of the men of the respective countries. The roadways 18, 19, 20 and 21 are in direct alignment with the spaces, 26, 27, 28 and 29, and these 10 spaces are also colored the national color of the respective countries, and indicate the entrance to roadways for the respective countries into Germany. The battle ground intermediate each one of the countries is 15 provided with a space 30, 31, 32 and 33 and these spaces have red crosses 34 marked thereon and indicate hospitals, the purpose of which will be also hereinafter more fully described. These spaces are also colored the 20 national color of the countries or camps which they represent. Certain of the spaces intermediate each of the countries are marked "Wounded" as at 35, "Advance" as at 36, "Rest Camp" as at 27, "Retreat" as at 25 38, and "Gassed" as at 39.

In playing, men indicated by the numeral 40 in Figure 3 of the drawings are used which can be made of relatively thick card board if so desired and colored to conform 30 to the national colors of the country which they indicate, and each country is to have four of these men. A pair of dice indicated by the numeral 41 is also utilized in playing the game.

35 Two or more players up to four can participate in the game simultaneously and the game is played in the following manner. The men 40 are placed at their home or base in the spaces 6, 7, 8 and 9 and the first player 40 then shakes the dice and rolls them out and if two sixes are rolled the player can move two men out on the battle ground on the space indicating the starting point. If one six and another number comes up the player 45 or nation moves one man out and takes as many spaces as the other number is. If no sixes come up the next nation has a turn to shake the dice and no men can enter the battle ground except by a number six, on one 50 dice. The men of the nation always move to the right and the nations or players also follow each other from the right in shaking the dice. Each player gets one turn and the men are brought out on the battle ground as 55 quickly as possible or as seen fit by the players as after a nation has one or more men on the battle ground it is not necessary to bring another man out if a six comes up on the dice. The following rules can be observed in playing the game.

60 1. When a nation has men on the runway or battle ground, it will take as many moves as possible. If a five and a two comes up on the device, the nation can move five with one 65 man and two with another, or seven with a

single man, but cannot move four with one and three with another man, unless a blockade is formed, (the term blockade will be hereinafter more fully explained) and then they must move as many spaces as possible, 70 which will be the space behind the blocked space or blockade.

2. A block or blockade is formed by one nation having two men on one space so no other men can pass by. On the space 37 75 marked "Rest Camp" two men of two different nations can rest, as it is a safety base for all nations, that is, no man can be sent home from this base, and two men on this base whether of the same nation or not forms 80 a block or blockade.

3. If a man moves on a space 36 marked "Advance" he can move forward five extra spaces. If a man moves on a space 38 marked "Retreat" he has to move backward 85 five spaces.

4. If a nation has to move its men on spaces 39 marked "Gassed" or "Wounded" the men so moved must return to their own nation's hospital, i. e., the spaces marked 30, 90 31, 32 or 33.

5. If a man moves on a space where another nation's man is, the man that was there first must return back to their own nation and start over again, as the man last moved 95 on the space sends the other nation's man back home.

6. Where men start from nations, that is the spaces 22, 23, 24, and 25 and hospitals of nations, that is the spaces 30, 31, 32, and 33, 100 are safety spaces for other nations, unless the nations that the spaces belong to send them home, that is, for instance, say Italy and France each has a man on England's hospital or space 31 or entrance to battle ground 105 or space 23, England enters the space 23 or hospital 31 the men on these spaces must return back to their own hospital space if on England's hospital space or sent back home when on England's space 23 if England's man comes out.

7. When a man lands on one of the spaces marked "Gassed" or "Wounded" and returns to their respective hospitals they cannot move the same man until the next turn. 115 When a nation's man advances, retreats or sends another nation's man back to their own nation, this man cannot be moved again until the player's next turn.

8. When a nation can only move with one 120 man the man must move as many spaces as the dice indicate. The entire amount must be moved unless blocked.

The play is continued along these lines until all of the men of one nation are in 125 the German territory at which time the nation having its men all in the German territory wins the game. Where nations enter into Germany that is, the spaces marked 26, 27, 28 and 29, does not represent 130

a safety space, but only indicates the road into Germany for the respective nations.

From the foregoing it can be seen that a game has been provided which will be a reminder of the World War, and which will be amusing and take considerable skill to play.

Changes in details may be made without departing from the spirit or scope of this 10 invention; but,

I claim:

1. In a game, a diagram comprising a plurality of marginal camps representing different countries, a central fortress representing an objective country, a battle ground surrounding the objective country, each of the camps having a gate leading to the battle ground, the battle ground being divided into spaces, roads leading from the 20 battle ground to the objective country, the road being divided into spaces, the first space of each road being colored to indicate the country which it represents, a set of men for each camp adapted to be moved 25 over the spaces, and means manually operated to indicate the number of spaces for moving each one of the men.

2. In a game, a diagram comprising a plurality of marginal camps, a central objective fortress, a battle ground divided into a plurality of spaces surrounding the fortress, certain of the spaces being colored

to represent the camps and arranged adjacent to the camps and defining the entrances of the camps upon the battle ground, 35 said spaces being safety spaces, a plurality of roadways leading to the objective country from the battle ground divided into spaces, the points of connection of the roadways with the battle ground being colored 40 to represent the camps, spaces arranged intermediate the camps colored to define safety hospital points, indicia written on certain other of the spaces for indicating certain moves, and separate men for each one of 45 the countries.

3. In a game, a diagram comprising a plurality of marginal camps, each of the camps representing a country and having a flag arranged therein, an objective country arranged intermediate the marginal camps, a tortuous roadway surrounding the central country defining a battle ground provided with a plurality of spaces, each of the camps having a lead out space colored to 50 represent the camp, a space for each camp colored to represent the camp having indicia thereon for indicating a hospital arranged forwardly of the lead off space, and indicia printed on other of the spaces for 55 defining moves for the men traversing the battle ground, and a set of men for each one of the camps.

HERBERT E. WENRICH.
